FASTENING MEANS AND COMBINATION

Samuel Hammer, New York, N. Y., assignor to
 United Metal Box Co., Inc., Brooklyn, N. Y., a
 corporation of New York

Application August 14, 1944, Serial No. 549,445

12 Claims. (Cl. 189—34)

1

The invention relates to a fastening means for securing a panel to a frame. The invention also relates to a combination of the panel and the frame carrying the fastening means for securing the panel thereto. The invention has particular applicability for securing the top of a cabinet such as a kitchen cabinet to the cabinet frame and also to secure a panel forming a sink or a sink and drain board to the frame which supports the same.

It is an object of the invention to construct a new and novel panel fastener which is easily and quickly operated to secure a panel to a frame.

It is another object of the invention to construct a combination of panel and frame having a new and novel fastening means for quickly and securely attaching the panel to the frame.

Another object of the invention is to construct a fastening means for securing a panel to a frame which firmly secures the panel thereto and which can be cheaply manufactured.

Other objects of the invention will be more apparent from the following description taken in connection with the accompanying drawings illustrating some preferred embodiments of the invention in which

Figure 1 is a cross section through a frame to which the panel is secured and showing the fastening means securing the panel to the frame.

Figure 2 is a longitudinal section through the frame and fastening means showing the manner in which the panel is secured to the frame.

Figure 3 is a partial view of the securing means in their initial position.

Figure 4 shows a mitered corner of the frame as it is formed from strip material.

Figure 5 is a longitudinal section through a frame and fastening means of a modified construction.

Figure 6 is a view of the fastening means in their initial position.

Figure 7 is a cross section taken on line 7—7 of Figure 5 through the frame and panel and showing fastening means securing the panel to the frame.

The fastening means is designed particularly for the top panel which may be used as a table top for a kitchen cabinet and the like. The fastening means however is applicable to securing any panel to a frame such as side panels and may be used to secure any table top to the frame which receives the same whether the top be flat or has an inclined, curved or vertical back portion. The panel may be a sink or a combination of sink and adjacent drainboard. Sinks as

2

presently manufactured, have a downwardly extending flange which extends beyond the side of the cabinet supporting the same. This flange is uneven or wavy and hence requires a narrow filler section between it and the adjacent cabinet in order to provide a continuous and tight construction therebetween. With a sink panel or a combination sink and drainboard panel secured to a frame by the construction to be described, the frame provides a flat frame edge against which the adjacent cabinet may be directly placed without the use of any filler structure. The construction has a very wide field of use and also embodies the combination of the panel and frame with the fastening means which secures the panel to the frame.

In Figure 1, a panel 10, that is illustrated being a table top for a kitchen cabinet, or the like, is fastened to a frame 12. The panel may have a downwardly or inwardly extending flange 11. The panel is to be secured to a frame 12 which has a shoulder 13 to engage the top surface thereof. This frame may be formed of strip material with mitered corners 15 as shown in Figure 4 so that bending the strip at the miter points forms the complete frame. The two ends of the strip are secured together to form the completed frame. The shoulder 13 for tables, cabinets and the like is a flange extending the full length of each side of the frame 12. Spaced from the shoulder 13 and preferably at the other edge thereof, the frame 12 may carry a groove or socket 14 which may be formed by bending the lower edge of the frame into a U.

The fastening means may be carried by a separate member which is secured to the frame in any suitable fashion. The fastening means shown includes an angle member 17 having an inwardly extending flange 18. The angle member shown is carried by the frame and received within the U thereof. The inwardly extending flange 18 carries at least one bendable tongue 19 and for table tops or panels of a substantial dimension a plurality of such tongues are utilized which are spaced closely together in order to obtain a continuous tight fit between the top and the shoulder 13 throughout the length thereof. Each tongue 19 may be punched or otherwise formed in the flange such as by forming the cutout 20 so that the tongue is free and may be easily bent when it is desired to secure a panel such as a sink, table top or the like to the frame. The tongues are spaced from the underside of the panel and are shown as parallel thereto although parallel relation is not essential. The

tongues and their respective bending axes are spaced from the panel so that each tongue must be bent in order to grip the panel between the shoulder and tongue. The tongues are shown as being at right angles to the adjacent frame, however, it is clear that they may be parallel with the frame.

The tongues may be more easily bent if they are provided in adjacent pairs as illustrated in Figure 4 and may be bent by forcing or hammering a U-shaped tool against the tongues as shown in Figure 2. Here the tongues are shown as being directed away from each other in initial position which is in the plane or substantially in the plane of the flange 18. The angle member may be one piece for each side of the frame or it may be many pieces secured to each side of the frame.

The panel 10 is positioned within the frame between the flange 18 of the angle member 17 and the shoulder 13. With this type of assembly the angular member 17 may be permanently secured such as by welding to the frame 12. The panel or table top 10 may be inserted within the frame before it is bent into final form or before the joining ends are secured together so that the frame can be opened up for insertion of the panel in position. The frame is then closed and the ends of the strip secured together such as by welding to form the finished frame. The frame with its panel is then attached to the cabinet or other supporting structure.

If desired the U 14 may form a socket for removably or insertably receiving the angle member. In such construction the frame may be completed, after which the panel 10 is inserted therein. The angle members are then inserted into the U-shaped socket 14. Each tongue 19 is then bent upwardly so that it engages the inner or underside of the panel 10. Since the bending axis of the tongue is spaced from the panel, the tongue is bent from a parallel or approximately parallel position with respect to the panel to a position in which it is perpendicular or at a steep angle with respect thereto. Preferably the tongues are of such length or slightly longer than the distance to the underside of the panel so that the end of the tongue bites into the inner side thereof. The tongue may or may not be distorted in the bending operation depending upon the length of tongue selected.

It is clear that the fastening means may be utilized with a panel or top which is slid into position from the fourth side. It is clear also that if it is desired to secure only two sides of the panel that a groove, socket or other means may be utilized to secure one side of the panel and the fastening means described may then anchor the opposite edge of the panel. In the preferred construction, however, and particularly for table tops, kitchen cabinet tops, and sinks, the panel is secured by the bendable fastening means on all four sides of the frame.

The fastening means described may also, if desired, be so located that the side edge 23 of the tongue engages the flange 11 of the panel. With this construction the panel 10 is securely anchored between the tongue and the shoulder 13 in a vertical or inward direction and also firmly anchored against lateral movement by the edge of the tongue engaging the flange 11. Such construction provides double anchorage for the panel.

In the construction of Figures 5 through 7, pairs of tongues 26, are cut into the angular member 27 so that the tongues are directed towards

each other. A tool may be utilized for forcing or hammering the tongues upwardly into contact with the panel 28. The angle member may be permanently anchored to the frame, or removable or insertable in the frame 29 in the same manner as described in connection with the construction of Figures 1 through 4.

The fastening means described has considerable advantage when the panel or table top is of some material such as fiber board or wood, the thickness of which may vary considerably for panels of supposedly the same dimension. The bendable tongues may distort or bend at their ends to accommodate for such variations in thickness as illustrated in Figure 5. For a relatively thin panel, there will be no or slight distortion of the ends of the tongue. For a panel of relatively greater thickness the end of the tongue may bend as it digs into the panel. The tongues, also, may have teeth 29 as shown in Figure 7 to dig into the panel and thereby more firmly anchor the same to the frame. A filler strip 30 may be used when insertable angle members are used.

This invention is presented to fill a need for improvements in a fastening means and combination. It is understood that various modifications in structure, as well as changes in mode of operation, assembly, and manner of use, may and often do occur to those skilled in the art, especially after benefitting from the teachings of an invention. Hence, it will be understood that this disclosure is illustrative of preferred means of embodying the invention in useful form by explaining the construction, operation and advantages thereof.

What is claimed is:

1. A panel fastener comprising a frame to receive the panel to be fastened, a shoulder carried by the frame at one edge thereof to engage one side of the panel, a U formed at the other edge of the frame, an angle member received in the U providing an inwardly extending flange spaced from the shoulder on the frame, at least one bendable tongue carried by the flange and adapted to be bent into contact with the panel to secure the same to the frame between the shoulder and the bent tongue.

2. A panel fastener to secure a panel having an angularly extending flange comprising a frame to receive the panel to be fastened, a shoulder carried by the frame at one edge thereof to engage one side of the panel, a plurality of bendable tongues carried by the frame and located with an edge of the tongue in position to engage the panel flange, the tongues being adapted to be bent with their ends into contact with the underside of the panel to secure the panel to the frame between the shoulder and the bent tongues and with an edge of the tongues engaging the panel flange to secure the panel against lateral movement.

3. A panel fastener to secure a panel having an angularly extending flange comprising a frame to receive the panel to be fastened having a shoulder to engage one side of the panel, an inwardly extending flange carried by the frame and spaced from the shoulder on the frame, at least one bendable tongue carried by the flange and its edge located adjacent the flange on the panel, the tongue or tongues being adapted to be bent into contact with the other side of the panel and the edge of the tongue into contact with the side of the panel flange to secure the panel to the frame.

4. A panel fastener to secure a panel having an angularly extending flange comprising a frame to

receive the panel to be fastened, a shoulder carried by the frame to engage one side of the panel, a U carried by the frame spaced from the shoulder, an angle member removably received in the U and having an inwardly extending flange which is spaced from the shoulder on the frame, a plurality of bendable tongues carried by the flange adjacent to the frame and adapted to be bent to bring the ends into contact with the other side of the panel and the edge of the tongue into contact with the panel flange to secure the panel to the frame.

5. A panel and panel fastener combination comprising a panel having a flange extending angularly therefrom, a frame to receive the panel having a shoulder to engage the outer side of the panel, an inwardly extending flange carried by at least one side of the frame and spaced from the shoulder on the frame, a plurality of bendable tongues carried by the flange and spaced from the panel, the tongues being adapted to be bent to bring each end into contact with the inner side of the panel and the edge of each tongue into contact with the panel flange to secure the panel to the frame.

6. A panel and panel fastener combination comprising a panel having a flange extending angularly therefrom, a frame to receive the panel having a shoulder to engage the outer side of the panel, a socket carried by the frame and spaced from the shoulder, means insertable in the socket and retained therein having an inwardly extending tongue flange spaced from the shoulder on the frame, a plurality of bendable tongues carried by each tongue flange and adapted to be bent to bring the end of each tongue into contact with the panel and the edge of each tongue into contact with the panel flange to secure the panel to the frame.

7. A panel fastener comprising a panel, a frame to receive the panel and having a shoulder to engage one side thereof, and means on the other side of the panel carried by the frame to secure the panel thereto including at least one pair of readily bendable tongues adjacent to each other and directed in opposite directions, the tongues having their bending axes spaced from the other side of the panel, each tongue being bent to a position substantially at right angles to the plane of the panel and into contact therewith to secure the panel to the frame between the shoulder and the bent tongues.

8. A panel fastener comprising a panel, a frame to receive the panel to be fastened having a shoulder to engage one side of the panel, and means on the other side of the panel carried by the frame to secure the panel thereto including at least one pair of readily bendable tongues adjacent to each other, the bending axis of each tongue being spaced from the panel, each tongue having a length from its bending axis slightly greater than the distance to the panel, the tongues being bent to a position substantially at a right angle with respect thereto and into contact therewith to secure the panel to the frame between the shoulder and the ends of the bent tongues.

9. A panel fastener comprising a panel, a frame to receive the panel to be fastened having a shoulder to engage one side of the panel, an inwardly extending flange carried by the frame and spaced from the shoulder on the frame and from

the other side of the panel, at least one readily bendable tongue carried by the flange, the tongue having its bending axis spaced from the panel and bent into a position substantially at right angles to the panel into contact therewith to secure the panel to the frame between the shoulder and the bent tongues.

10. A panel fastener comprising a panel, a frame to receive the panel to be fastened having a shoulder to engage one side of the panel, an inwardly extending flange carried by the frame and spaced from the shoulder on the frame and from the other side of the panel, at least one pair of readily bendable tongues carried by the flange adjacent to each other, each pair of tongues extending in opposite directions and having their bending axes spaced from the other side of the panel, each tongue being bent to a position substantially at right angles with respect to the panel into contact therewith to secure the panel to the frame between the shoulder and the bent tongue.

11. A panel fastener comprising a panel, a frame to receive the panel to be fastened having a shoulder to engage one side of the panel, an inwardly extending flange carried by the frame and spaced from the shoulder on the frame and from the other side of the panel, a least one readily bendable tongue carried by the flange, each tongue having its bending axis spaced from the panel and having a length slightly greater than the distance from its bending axis to the panel, the tongues being bent to a position substantially at right angles with respect to the panel to bring the end of the tongue into contact therewith to secure the panel to the frame between the shoulder and the end of the bent tongue.

12. A panel fastener comprising a panel, a frame to receive the panel to be fastened having a shoulder to engage one side of the panel, an inwardly extending flange carried by the frame and spaced from the shoulder on the frame and from the other side of the panel, at least one pair of readily bendable tongues carried by the flange adjacent to each other, each tongue having its bending axis spaced from the panel and having a length slightly greater than the distance from its bending axis to the panel, the tongues being bent to a position substantially at right angles with respect to the panel to bring the ends of the tongues into contact therewith to secure the panel to the frame between the shoulder and the ends of the bent tongues.
